UNITED STATES PATENT OFFICE.

RENÉ SAVOYE, OF SEVRAN, AND URBAIN DRÝVERS, OF PARIS, FRANCE.

AUTOMATIC MUSICAL INSTRUMENT WITH PNEUMATIC CONTROL.

1,125,733.

Specification of Letters Patent.

Patented Jan. 19, 1915.

Application filed December 9, 1912. Serial No. 735,842.

To all whom it may concern:

Be it known that we, RENÉ SAVOYE, a citizen of the Republic of France, and a resident of Sevrain, Seine and Oise, France, and URBAIN DRÝVERS, a subject of the King of Belgium, and a resident of 3 Rue des Immeubles Industriels, Paris, France, have invented certain new and useful Improvements in Automatic Musical Instruments with Pneumatic Control, of which the following is a specification.

This invention relates to improvements in or relating to automatic pneumatically controlled musical instruments.

Only an extremely limited space is available in ordinary pianos within which pneumatic control mechanism may be arranged. It is highly desirable therefore in such mechanism to reduce the space occupied by the pneumatic parts to the greatest extent possible. Moreover, it is advantageous to reduce as far as possible the number of parts which form the pneumatic device and also to unite these various parts in such manner that they are easily accessible and taken to pieces.

The present invention provides a construction designed to attain these ends.

Two constructions embodying the invention are illustrated by way of example in the accompanying drawing.

Figures 1 to 7 relate to the first construction; Fig. 1 is a cross section through the pneumatic mechanism at corresponding valves in the primary and secondary wind chests; Fig. 2 is a section on line 2—2 of Fig. 1, showing two groups of parts; Fig. 3 is a section on line 3—3 of Fig. 1, showing also two groups of parts; Fig. 4 is a plan of portion of the secondary wind chest showing valve apertures; Fig. 5 is a plan of a valve box for the secondary wind chest; Fig. 6 is a plan of the diaphragm box of the secondary; Fig. 7 is a plan of the diaphragm box of the primary; Fig. 8 is a longitudinal section through the axis of the parts of one of the notes; Fig. 9 is a section on line 9—9 of Fig. 8; Fig. 10 is an inverted plan of a modified form of valve box for the secondary; Fig. 11 is a plan of a modified form of diaphragm box for the secondary.

The wind pipe or air chamber of the secondary valve is formed by a metallic tube A (Figs. 1, 2, 3, 4, 8 and 9) of rectangular section and common to all the notes. The

tube A is provided, for each note, with a hole for the diaphragm a^1 and a hole for the valve a ; the latter hole is provided with a raised edge which serves as a seat for the valve a . The mechanism moreover comprises, for each note, a bellows, a valve box and a diaphragm cap. The bellows is of known type. The valve box is made of metal and is formed either by a cast part B (Figs. 1, 2 and 5) or by a stamped out part B¹ (Figs. 8, 9 and 10). The cap is made of metal and formed either by a cast part C (Figs. 1, 2 and 6) or by a stamped out part C¹ (Figs. 8, 9 and 11).

The bellows, the valve box (B or B¹) and the cap (C or C¹) are connected together and kept on the tube A by means of four bolts.

The wind pipe or air chamber of the "primary" valve is constituted by a metallic tube A² of rectangular section and common to all the notes. The tube A² is provided, for each note, with a hole for the diaphragm e and with a hole for the valve b .

The primary valve mechanism comprises also a valve box and diaphragm cap for each note-operating mechanism. The valve tube is constituted by a metallic tube D soldered onto the tube A²; the tube D is provided with a branch e^1 which connects it to the cap (C or C¹) of the secondary valve. The diaphragm cap E is made of metal and is formed either by a cast part (Figs. 1, 3 and 7) or by a stamped out part similar to the cap C¹ of the secondary valve. The diaphragm cap E is fixed by four small bolts onto the web of an angle-iron secured to the pipe A².

The arrangement just described has all the advantages inherent to wind chests entirely made of metal; the manufacture thereof is economical and they are always air tight.

The height of the said arrangement is less than that of the arrangements hitherto known. Moreover the pieces can be mounted and taken to pieces extremely easily, making it possible to easily control the working of each note.

The operation of the apparatus is the usual one. The tube which opens to the diaphragm box E of the primary communicates with the tracker board (not shown). The usual foot pumps, (not shown) suck air through the tubes A and A². When the perforation in the music roll passes over an

aperture in the tracker bar the tube leading to the diaphragm *e* is opened, the diaphragm rises lifting also the double valve *b*. The latter thus opens at its upper end to 5 atmosphere and communication with the secondary is established through the pipe *c*. Immediately the suction in the tube *A* lifts the diaphragm *a*¹ and with it the valve *a*. The valve *a* being lifted, communication is 10 established with the bellows and the latter is depressed by the suction in the tube *A*, thus actuating the mechanism of the instrument in well known manner.

We claim as our invention:—

- 15 1. In a device of the character described, a pneumatic control system having a wind chest comprising a flattened rectangular metallic tube common to all the notes and apertured on its opposite faces to receive on one 20 face a valve and on the other face a diaphragm, in combination with a pair of recessed metallic members for each note arranged on opposite sides of said tube with their recesses in register with the apertures 25 in the latter and forming respectively a valve box and a diaphragm box, together with bolts common to said recessed metallic members, passing through the same outside the area of the wind chest and serving to hold said members in assembled position on 30 the wind chest, substantially as described.
2. In a device of the character described, a pneumatic control system having a wind chest comprising a flattened rectangular metallic tube common to all the notes and apertured on its opposite faces to receive on the one face a valve and on the other face a diaphragm, in combination with, for each 35 note, a tube soldered in the valve aperture 40 to form a valve box, and a recessed metallic member with recess in register with the diaphragm aperture to form a diaphragm box and bolts passing through said diaphragm

box outside the area of the wind chest to hold said parts assembled, substantially as 45 described.

3. In a pneumatic control system for automatic musical instruments of the type described, a wind chest comprising a flattened rectangular metallic tube common to all the notes and apertured on its opposite faces to receive on one face a valve and on the other face a diaphragm, in combination with, for each note, a member recessed to form a diaphragm box arranged transversely of the wind chest and having portions extending beyond the opposite sides of the latter, together with means engaging the opposite sides of said diaphragm box outside the area of the wind chest and serving to hold the same in assembled position on said wind chest, substantially as described.

4. In a pneumatic control system for automatic musical instruments of the type described, a wind chest comprising a flattened rectangular metallic tube common to all the notes and apertured on its opposite faces to receive on one face a valve and on the other face a diaphragm, in combination with, for each note, a single integral metallic member above and a single integral metallic member below the wind chest, each recessed to form a box, the one for a valve and the other for a diaphragm, and means for securing said recessed members in adjusted position in 70 register with the holes in the opposite faces of the wind chest, substantially as described.

In testimony whereof we have signed our names to this specification, in the presence of two subscribing witnesses.
